UNITED STATES PATENT OFFICE.

MAXWELL C. MAXWELL, OF STAMFORD, CONNECTICUT, ASSIGNOR TO THE YALE & TOWNE MANUFACTURING COMPANY, OF STAMFORD, CONNECTICUT.

CYLINDER LOCK.

Application filed August 2, 1926. Serial No. 126,556.

This invention relates to improvements in cylinder locks,—one object of the invention being to provide simple and efficient means to secure a rotatable member against longitudinal displacement from the bore of another member.

A further object is to provide the plug of a cylinder lock with a hardened cap and to secure said cap and plug against longitudinal displacement or withdrawal from the cylinder.

With these and other objects in view, the invention consists in certain novel features of construction and combinations of parts as hereinafter set forth and pointed out in the claims.

In the accompanying drawings,—

Figure 1 is a sectional view of a cylinder lock showing an embodiment of my invention.

Figure 2 is a transverse sectional view with the securing wire omitted.

Figure 3 is a transverse sectional view showing the securing wire in place.

Figure 4 is a view in elevation showing the plug and its cap, and

Figure 5 is a longitudinal sectional view of the construction shown in Figure 4.

The cylinder or casing of a cylinder lock is represented at 1 and the plug of the lock is shown at 2. The lock plug is provided at its headed end with a hardened steel cap 3 which may be secured thereto by forcing it on said headed end of the plug or in any other suitable manner. The peripheral flange 4 of the cap 3 is provided with an annular groove 5 and the inner wall of the cylinder 1 is provided near its outer end with a groove 6 to mate with the groove 5.

A hole 7 is made in the wall of the cylinder 1 and is tangential to the mating grooves 5 and 6. A locking wire 8 is passed through the tangential hole 7 and made to enter the mating grooves 5 and 6 in the plug cap and cylinder wall respectively. The outer end of the locking wire will be forced inwardly past the outer face of the cylinder 1 and a plug 9 may be inserted in the hole behind the end of the wire or said plug may be omitted.

With my improved construction, the plug will be provided with a hardened steel or

armor cap and this cap is utilized as part of means for securing the plug against longitudinal displacement relatively to the cylinder. The securing wire is prevented from turning by reason of one of its ends entering or being disposed in the tangential hole 7 in the cylinder and said securing wire, while preventing longitudinal displacement of the plug, will permit free rotary movement of said plug during the normal operation of the lock.

While I have described my improvements in connection with a cylinder lock, it will be understood that the fastening means may be applied in any construction embodying a cylinder which receives in its bore a rotatable member.

Having fully described my invention what I claim as new and desire to secure by Letters-Patent, is:

1. The combination of a cylinder and a rotary member therein, said cylinder and member having parts formed with mating grooves and said cylinder having a tangential hole, and a fixed, continuous securing member occupying said mating grooves and extending into said tangential hole.

2. The combination of a cylinder of a cylinder lock, said cylinder having an annular groove in its inner wall near one end and also having a tangential hole communicating with said groove, a plug member in said cylinder, an armor cap on one end of said plug member and having an annular groove mating with the annular groove in the cylinder, and a locking member occupying the mating annular grooves in the cylinder and cap and having one end disposed in the tangential hole in the cylinder.

3. A plug and cylinder assembly including a cylinder having a groove in the plug bore and also having a tangential hole leading into said groove, the plug having a groove mating with the cylinder groove, and a securing member lying partially in said tangential hole and partially in the mating grooves, the tangential portion acting to prevent movement of said securing member.

In testimony whereof, I have signed this specification.

MAXWELL C. MAXWELL.

CERTIFICATE OF CORRECTION.

Patent No. 1,637,953.

Granted August 2, 1927, to

MAXWELL C. MAXWELL.

It is hereby certified that error appears in the printed specification of the above numbered patent requiring correction as follows: Page 1, line 85, claim 2, strike out the words "an armor" and insert the article "a"; and that the said Letters Patent should be read with this correction therein that the same may conform to the record of the case in the Patent Office.

Signed and sealed this 13th day of September, A. D. 1927.

M. J. Moore,
Acting Commissioner of Patents.

Seal.
